AIR CONDITIONER

Leonard Ashbach, Chicago, Ill., and Lionel Marks,
New York, N. Y.

Application July 12, 1954, Serial No. 31,396

Term of patent 14 years

(Cl. D62—4)

Fig. 1

Fig. 2

To all whom it may concern:

Be it known that we, Leonard Ashbach and Lionel Marks, residing at Chicago, Illinois, and New York, New York, respectively, have invented a new, original, and ornamental Design for Air Conditioners, of which the following is a specification, reference being had to the accompanying drawings, forming a part hereof.

Figure 1 is a front perspective view of an air conditioner showing our new design; and

Figure 2 is a rear perspective view.

We claim:

The ornamental design for an air conditioner, as shown.
